UNITED STATES PATENT OFFICE

PAUL W. H. DEWITZ, OF KANSAS CITY, MISSOURI; HELEN J. DEWITZ, WIDOW OF SAID PAUL W. H. DEWITZ, DECEASED, ASSIGNOR, BY MESNE ASSIGNMENTS, TO FLORENCE BLANFORD, OF KANSAS CITY, MISSOURI

VENDING MACHINE

Application filed May 31, 1927, Serial No. 195,440. Renewed June 4, 1931.

My invention relates to vending machines, and more particularly to a machine for vending combinations of articles, such as paper, envelopes and postage stamps.

5 It is a purpose of my invention to provide a vending machine of the above mentioned character that is particularly adapted for use in public or semi-public places, such as hotels, for vending a combination of writing

10 paper, envelopes and postage stamps, thus making it possible to dispense with a supply of envelopes and writing paper unrestrictedly open to the public, such as is now commonly the case in places of this character.

15 It is very commonly the case, in hotels and similar places, that the general public makes use of the envelopes and writing paper furnished for the use of guests by the hotel and that this makes the expense of the same

20 many times what it would be if the use thereof were restricted to legitimate purposes. By the use of my invention this expense is avoided and the paper and envelopes as well as the postage stamps are paid for

25 by the user.

It is a further purpose of my invention to provide a machine of the above mentioned character that is simple in construction and simple to operate, and which will not get 30 out of order easily. Furthermore, said machine is preferably so constructed that the mechanism therein is readily accessible in case it is necessary to adjust or repair the same.

35 It is a particular purpose of my invention to provide a vending machine having a drum provided with a plurality of radially arranged partitions forming compartments or sector-shaped pockets therein for receiving 40 the articles to be vended, said articles being delivered from said drum, upon the actuation of suitable operating means, to the exterior of said machine, by the action of gravity.

45 It is a further object of my invention to provide means for rotating said drum step by step so that the article holding pockets therein will be successively moved into vending position. A housing is provided around the lower portion of the drum so that the 50 articles in the lower portion of the drum,

which is mounted to rotate on a horizontal axis, will not be inadvertently discharged therefrom and said housing is provided with a slot aligning with a chute by means of which the articles are discharged from the 55 machine, said slot aligning with the pocket or compartment of the drum that is in vending position and all the other pockets being out of alignment therewith.

The step by step actuating means 60 comprises means for rotating the drum in one direction and means for holding the same against rotation in said direction. In the form of the invention shown, which is the preferred form, the said means comprises a 65 pair of ratchet wheels, a pawl for rotating one of said ratchet wheels and a stop finger for holding the other ratchet wheel against rotation, the teeth of said ratchet wheels being oppositely directed so that the stop finger holds the drum from rotating in the direction in which the same would be normally rotated by means of the pawl. Said means further comprises means for disengaging 70 said stop finger from the holding ratchet and means for actuating the actuating pawl, said last mentioned means operating said stop finger disengaging means through a coin inserted into the machine, whereby the machine is coin controlled. 75

It is also an object of my invention to provide means whereby said drum can be released for filling purposes and to further provide a shutter for closing the slot so that the articles in the machine will not be discharged while the drum is being rotated during the filling operation. The upper portion of the drum is accessible for filling purposes when the outer casing of the machine is opened, 80 inasmuch as the housing does not extend 90 around the upper portion of the drum.

Other objects and advantages of the invention will appear as the description of the drawings proceeds. I desire to have it 95 understood, however, that I do not intend to limit myself to the details of construction shown or described, but that I intend to include as part of my invention all such obvious changes and modifications as would occur 100

to a person skilled in this art and as would fall within the scope of the claims.

In the drawings:

Fig. 1 is a perspective view of my improved vending machine, partly broken away.

Fig. 2 is a vertical longitudinal sectional view thereof, with the drum omitted.

Fig. 3 is a detail elevational view of a portion of the operating mechanism in changed position.

Fig. 4 is a central vertical longitudinal section.

Fig. 5 is a horizontal sectional view of said machine, the operating mechanism being shown in plan.

Fig. 6 is a fragmentary perspective view of the ratchet wheels and a portion of the operating mechanism co-operating therewith.

Fig. 7 is a perspective view of a portion of the ratchet actuating pawl and guide separated.

Fig. 8 is a similar view of the stop finger and stop releasing means, and

Fig. 9 is a fragmentary perspective view of the shutter operating handle and the holding means therefor.

Referring in detail to the drawings, my improved vending machine comprises a cabinet or outer casing having a bottom 10, hinged rear wall 11, side walls 12, a front wall 13 and a top 14. The rear wall 11 is held in closed position by means of the lock 15.

Removably mounted within the outer casing or cabinet is the vending apparatus comprising a pair of side plates 16 which are secured together by means of the rods 17, secured by the screws 18. Mounted in bearings 19 provided in said side plates is the shaft 20.

The shaft 20 extends through a hardwood spool or hub member 21 slotted to receive the radially extending plates or partition members 22, of which any desired number may be provided. The hub member 21 also has the disks 23 secured thereto at opposite ends thereof. Said disks being slotted to receive the ears 22' on the plates 22 for securing said plates and disks together. A

drum provided with a plurality of sector-shaped pockets is thus provided on the shaft 20, the disks 23 forming the end walls of said pockets. The plates 22 are equidistantly spaced around the hub, and thus provide pockets or compartments of uniform size around the drum.

A pair of transversely extending bars 24 are also provided between the side plates 16, said bars having down-turned ends 25 secured in any desired manner to said side plates. Supported from said bars 24 is a housing or guard member 26 substantially semi-cylindrical in form and embracing the lower half of the drum, said guard member being slightly spaced from the drum to per-

mit rotation thereof. Said guard plate is provided with a transversely extending slot 27 and a guide member or chute 28 extends from the slot 27 to the discharge opening 29 in the front wall 13 of the cabinet. The chute 28 is carried by the side plates of the vending apparatus, and is secured thereto in any desired manner. The slot 27 is of such a width that the same will align with the open end of any one of the compartments of the drum, but is of such a size that only one of said compartments will be capable of discharging its contents by gravity through said slot, at one time.

Mounted on one end of the shaft 20 beyond one of the side plates 23 is a hub member 30, which may be of any desired material, in the present case being made of wood. Mounted on opposite ends of said hub member 30 are the ratchet wheels 31 and 32, the same being secured to said hub 30 in any desired manner. A spacing member 33 is mounted between the ratchet member 31 and the side plate 23 adjacent thereto, and said hub 30 is secured to the hub 21 by means of fastening elements 34.

Upon reference to Fig. 6 it will be seen that the teeth on the ratchet wheels 31 and 32 are inclined in opposite directions. Thus the teeth 35 on the wheel 31 are so inclined that the wheel 31 can be driven in a clockwise direction by means of a pawl co-operating with said teeth, and the teeth 36 on the wheel 32 are so inclined that a holding finger engaging therewith will hold the same from movement in a clockwise direction. Suitable means is provided for advancing the ratchet wheel 31 one tooth at a time in a clockwise direction and as the number of teeth on the wheel 31 and also on the wheel 32 corresponds to the number of compartments in the drum each movement of the ratchet wheel 31 in its step by step rotation will bring one of the compartments in alignment with the slot 27, to discharge the contents thereof through said slot by the action of gravity.

The means for actuating the ratchet wheel 31, comprises a lever 37 pivoted at 38 on one of the side plates 16 and having an end portion 39 extending through a slot 40 in the front wall 13 of the cabinet. Detachably secured to the end portion 39 of the lever 37 in any suitable manner is the handle or knob 41. The lever 37 is provided with an offset 42 therein from which the headed pivot member 43 projects. The pivot member 43 extends through a slot 44 in the pawl member 45 having a laterally extending tooth 46 adapted to engage with the teeth 35 on the ratchet wheel 31. The pawl 45 is also provided with a laterally projecting ear 47 extending in an opposite direction to the tooth 46, said ear being slidably mounted in the open ended slot 48 formed between the bifurcations 49 provided on the offset end 50 of the arm 51 se-

cured in fixed position, in any preferred manner, to the one side plate 16. The slot 48 is provided with a bevelled wall portion 52 and the ear 47 has a correspondingly bevelled edge portion 53. The finger 47 being smaller than the slot 48, said bevelled portions co-operate to guide the tooth 46 into proper co-operative relation to the teeth 35 to rotate the ratchet wheel 31 in a clockwise direction (in Fig. 6), the lower edge 54 of said tooth 46 being bevelled to properly engage with the teeth 35. The lever 37 is provided with a spring 55 having one end engaged in an eye 56 in the lever 37 and the other end engaged with a hook 57 on the plate 16, for holding the lever normally in an upward, retracted position.

The cabinet front wall 13 is provided with a coin slot 58 from which the coin guide 59 extends to the stop releasing lever 60 pivoted to the side plate 16 at 61. Said stop releasing lever 60 has the plate 62 secured to the lower end thereof, said plate having a curved end 64 extending beyond the end of the lever thus providing a shoulder at 63 on said lever with which the coin 65 engages as it reaches the end of the coin guide 59. The coin is held in position between the shoulder 63 and the end of the bottom of the guide 59 and beside the plate 62 until the lever 37 is actuated as will be explained below.

Pivoted on the side plate 16 at 66 is the stop finger 67 having the laterally extending tooth 68 having the bevelled edge 69 engaging the teeth 36 on the ratchet wheel 32 to hold the same against rotation in a clockwise direction (in Fig. 6). The stop finger is held normally in engagement with the ratchet wheel by means of the spring 70 having one end engaged in the eye 71 in the member 67 and the other end engaged around the screw 72 mounted in the side plate 16.

The stop finger 67 is provided with a reduced end portion 73 projecting beyond the tooth 68 which is located above the laterally projecting lug 74 on the lever 60 so as to be in position to be engaged thereby. A guide plate 77 having the outwardly offset central portion 78 is mounted on the plate 16, said offset portion receiving the slide 79 having the finger piece 80 and the stop lug 81 on the end thereof. The slide 79 is further provided with the bevelled edge portion 82 and the cam portion 83 between which the oppositely inclined edge portion 84 is provided, on the offset end 85 of said slide. The lug 74 normally rests in the angle formed between the cam portion 83 and the edge 84, and is out of engagement with the reduced end 73 of the stop finger 67.

The lever 37 has a rod 86 pivoted in the offset 42 therein, at one end thereof, and has the opposite end 87 thereof pivoted in an opening in the plunger 88. The plunger 88 is slidably mounted in the outwardly offset

portion 89 of the guide plate 90. The plunger has a bevelled edge portion 91 and a relatively blunt end 92 adapted to engage with the coin 65 as the plunger is moved downwardly. The angularity of the shoulder 64 to the guide 59 is such that if the proper size coin is inserted in the slot 58 and reaches the position shown in Fig. 6, the plunger will wedge the lever 60, by means of the coin, to turn the same on its axis, as shown in Fig. 3, lifting the lug 74 off the slide 79 and disengaging the tooth 68 from the ratchet wheel 32. After this has occurred, due to provision of the slot 44, the pawl 45 is rocked advancing the ratchet wheel 35 one tooth in a clockwise direction (in Fig. 6), whereupon the stop member again engages with the ratchet wheel 32 and the other parts resume their original position.

In order to fill the machine without discharging the contents thereof the curved shutter 93 is provided, said shutter being guided in its movements by means of the guide flanges 94 and being actuated so as to be moved into position over the slot 27 and out of such position, by means of the lever 95 having the link 96 pivoted thereto and to the shutter 93, said lever having a portion 97 extending transversely of the drum at one side thereof, and journalled in brackets 98 provided on the one side plate 16. Said lever also has the operating handle portion 99 extending across the rear side of the machine normally engaged with the hook 100 on the cross bar 24, but movable downwardly out of such position to move the shutter over the slot 27.

To fill the machine the hinged rear wall is swung to open position, the handle 99 is operated to move the shutter in front of the slot 27 and the slide 79 is moved toward the rear of the machine, until the shoulder 101 engages with the guide 77. As the slide is moved rearwardly, the lug 74 rides up on the inclined cam surface 83, and raises with it the stop finger 67, releasing the tooth 68 from the ratchet wheel 32. This permits the drum to be rotated by hand in the direction in which it is normally actuated by the pawl 45, and permits filling of all the empty compartments of the drum. The machine is reset for operation by pushing the slide 79 forwardly until the lug 81 engages the guide 77, permitting the lug 74 and the stop finger 67 to return to normal position due to action of the spring 70. The handle 99 is then actuated to move the shutter out of alignment with the slot 27 and the pivoted rear wall 11 closed and locked. When the shutter 93 is moved away from over the slot 27 the articles in the compartment in alignment therewith are fed through the slot and out of the machine by gravity. Thus one compartment is always empty when the machine starts operation, and if any definite number of articles are to be vended with each filling of the machine, the

105

110

115

120

125

130

number of compartments in the drum must exceed that by one.

The articles preferably vended by my machine are two envelopes 102, four sheets of paper 103 and two two-cent postage stamps 104. The various articles included in this combination may be held in proper assembled relation by means of a clip 105, or any other preferred holding means may be provided.

10 The combination of articles referred to above is preferably vended for five cents, and the coin 65 is in such case a five cent piece, there being, of course one set of the articles referred to above provided in each compartment of the drum. After the coin 65 has been forced downwardly by means of the plunger 88, the same drops into the coin chute 106 provided below the coin guide 59, and travels along the same until it passes out through 20 the slot 107 into the coin box 108. The coin box 108 is detachably secured to the one side plate 16 by means of the screws 109 passing through the keyhole slots 110 in the box 108.

Having thus described my invention, what 25 I desire to claim and secure by United States Letters Patent is:

1. In a vending machine, a drum mounted for rotation about its axis, and means for rotating said drum step by step comprising a 30 pair of ratchet wheels having oppositely directed teeth, a pivoted operating lever, a pawl connected therewith and engaging one of said ratchet wheels to rotate the same, a stop member normally engaging the other of said 35 ratchet wheels and coin-controlled means for disengaging said stop member from its ratchet wheel.

2. In a vending machine, a drum mounted for rotation about its axis, and means for rotating said drum step by step comprising a 40 pair of ratchet wheels having oppositely directed teeth, a pivoted operating lever, a pawl connected therewith and engaging one of said ratchet wheels to rotate the same, a stop member normally engaging the other of said 45 ratchet wheels and coin-controlled means for disengaging said stop member from its ratchet wheel prior to actuating said pawl to rotate its ratchet wheel the distance 50 of one tooth, comprising a coin engaging plunger connected with said pivoted lever.

3. In a vending machine, a drum mounted for rotation about its axis, and means for rotating said drum step by step comprising 55 a pair of ratchet wheels having oppositely directed teeth, a pivoted operating lever, an arm pivotally carried thereby and comprising a pawl engaging one of said ratchet wheels to rotate the same, means for guiding 60 the movements of said pawl, a stop member normally engaging the other of said ratchet wheels and coin controlled means for disengaging said stop member from its ratchet wheel.

65 4. In a vending machine, a drum mounted

for rotation about its axis and means for rotating said drum step by step comprising a pair of ratchet wheels having oppositely directed teeth, a pawl engaging one of said ratchet wheels, a stop member normally engaging the other of said ratchet wheels and means for disengaging said stop member from its ratchet wheel, comprising a 70 slidable cam member and means for moving said cam member to raise said stop away from its ratchet wheel.

5. In a vending machine, a drum mounted for rotation about its axis, and means for rotating said drum step by step comprising a pair of ratchet wheels having oppositely directed teeth, a pawl engaging one of said ratchet wheels, a stop member normally engaging the other of said ratchet wheels and coin controlled means for disengaging said 80 stop member from its ratchet wheel, comprising a pivoted lever having means thereon for raising said stop member away from said ratchet wheel, a hand lever connected with said pawl and a plunger actuated by said hand lever to impinge a coin against said 85 pivoted lever whereby the same is rocked to raise said stop member.

6. In a vending machine, a drum mounted for rotation about its axis, a holding ratchet wheel thereon, a stop member engaging said 90 ratchet and means for disengaging said stop member from its said ratchet comprising a slidable cam member and means for moving said cam member to raise said stop away from said ratchet wheel.

100 7. In a vending machine, a drum mounted for rotation about its axis, and means for rotating said drum step by step comprising a pair of ratchet wheels having oppositely directed teeth, an elongated arm having a pawl on the end thereof engaging one of said ratchet wheels, means for holding said pawl in engagement therewith, a hand lever loosely pivotally connected with said elongated arm, a stop member, and coin-controlled means for releasing said stop member connected with said hand lever and comprising a pivoted arm engaging said stop member to raise the same off its ratchet wheel.

110 8. In a vending machine, a drum mounted for rotation about its axis, and means for rotating said drum step by step comprising a pair of ratchet wheels having oppositely directed teeth, a pawl engaging one of said ratchet wheels, and a stop member normally 115 engaging the other of said ratchet wheels, coin controlled means for disengaging said stop member from its ratchet wheel and means independent of said coin controlled means for disengaging said stop member from its ratchet wheel.

120 9. In a vending machine, a drum mounted for rotation about its axis, and means for rotating said drum step by step comprising a pair of ratchet wheels having oppositely 125 di-

70

rected teeth, an operating lever pivoted near one end thereof, an arm loosely pivoted on said lever, a pawl on the opposite end of said arm engaging one of said ratchet wheels to rotate the same, a pivoted stop member engaging the other of said ratchet wheels, a pivot arm adapted to engage said stop member to disengage the same from said ratchet wheel and coin controlled means for moving said last mentioned arm on its pivot comprising a coin engaging plunger and means connecting said plunger with said lever.

10. In a vending machine, a drum mounted for rotation about its axis, and means for rotating said drum step by step comprising a pair of ratchet wheels having oppositely directed teeth, an operating lever pivoted near one end thereof, a pawl on the opposite end of said arm engaging one of said ratchet wheels to rotate the same, a pivoted stop member engaging the other of said ratchet wheels, a pivot arm adapted to engage said stop member to disengage the same from said ratchet wheel, coin controlled means for moving said last mentioned arm on its pivot comprising a coin engaging plunger and means connecting said plunger with said lever and a slideable cam device for disengaging said stop member from said ratchet wheel independently of said coin controlled means.

In testimony whereof, I hereunto subscribe my name this 26th day of May, 1927.

PAUL W. H. DEWITZ.
